UNITED STATES PATENT OFFICE.

JAMES M. SHANAHAN, OF BROOKLYN, NEW YORK.

DESIGN FOR TRIMMING.

Specification forming part of Design No. 11,291, dated July 8, 1879; application filed May 3, 1879.
[Term of patent 3½ years.]

To all whom it may concern:

Be it known that I, JAMES M. SHANAHAN, of Brooklyn, in the county of Kings and State of New York, have invented or originated a new Design for Trimming, of which the following is a full, clear, and exact description, reference being had to the accompanying drawings, making part of this specification.

This design is adapted to fluted or quilled trimmings of any desired width, the design or ornamentation being embossed or in relief.

The design consists, essentially, of two border rows of parallel flutings arranged crosswise of the strip of material, and a row or rows of oblique pyramidal frusta arranged centrally on the strip of goods between the border flutings.

In the drawings, Figure 1 shows a strip of trimming ornamented according to my design, and having one row of the oblique pyramidal frusta. Fig. 2 shows a wider strip, in which two rows of the frusta are employed, the elements of the design and the arrangement being the same as that in Fig. 1. Fig. 3 is a section of Fig. 1, arranged to show the relief or elevation of the elements of the design.

In all of these figures, A A represent the usual border flutings or quillings, and B the ob-

lique pyramidal frusta. The bases and apexes of the latter are of diamond shape, and they are arranged in line from end to end of the trimming, or lengthwise of the same, parallel with the border rows of flutings.

What I claim as my design is—

1. The design for trimming, which consists of border flutings A, and pyramidal frusta B, substantially as described, and shown in the accompanying drawings.

2. The design for trimming, which consists of two raised border rows of flutings, A A, and an intermediate row of oblique pyramidal frusta, B, substantially as described, and shown in the accompanying drawings.

3. The design for trimming, which consists of a centrally-arranged row or rows of oblique pyramidal frusta and two rows of border flutings or quillings parallel to the central row or rows, and in relief, substantially as described, and shown in the accompanying drawings.

In witness whereof I have hereunto signed my name in the presence of two subscribing witnesses.

JAMES M. SHANAHAN.

Witnesses:

ARTHUR C. FRASER,
HENRY CONNETT.
